Patented Feb. 27, 1923.

UNITED STATES PATENT OFFICE.

OSCAR T. HOBSON, OF TOLBERT, TEXAS.

CULTIVATOR-GANG EQUALIZER.

Application filed March 2, 1921. Serial No. 449,095.

To all whom it may concern:

Be it known that I, OSCAR T. HOBSON, a citizen of the United States, residing at Tolbert, in the county of Wilbarger and 5 State of Texas, have invented a new and useful Cultivator-Gang Equalizer, of which the following is a specification.

My invention relates to improvements in the control of cultivator gangs and is especially adapted for use on cultivators of the 10 pivot frame and the pivot axle classes.

The objects of my invention are, first, to cause the gangs to continually sit square with the row and thereby plow equal and parallel strips on both sides of the row; second, to make the gangs easier to guide; and third, to accomplish the two above named objects 15 without hindering the adjustment of the spacing between gangs by means of the adjustable spread arch.

I accomplish these objects by the mechanism illustrated in the accompanying drawing in which,

Figure 1 is a perspective view of part of 25 a cultivator embodying the front arch, the front part of the gangs, the spread arch, and the invention connected therewith.

Fig. 2 is a perspective view from the same 30 angle showing the new parts disconnected from the old structure.

This invention applies to cultivators in which the gangs 1 1' (of which only the front parts are shown) are fastened to the legs 2 2' of the front arch by the couplings 3 3' such that the gangs 1 1' may swing laterally about the pivots 4 4'.

An operable connection between the two gangs is provided by the U-bolt clamps 5 5', the connecting rods 6 6', the crank arms 7 7', 40 the shafts 8 8' which are journaled to the front arch by the hangers 9 9', and the crank-arms 10 10'. The crank-arms 7, 7', 10, 10' are securely fastened to the shafts 8 8' by set screws. Crank-arms 10 10' have 45 the effect of gear segments gearing the two shafts 8 8' together such that they will turn in opposite directions. The ball and the recess take the place of a number of teeth in mesh whose angle of action is sufficient to 50 take care of any variation in the spacing of the gangs. The final form of the eyes 12 12' in the crank-arms 7 7' are made by a special reamer attached to a drill press, while the eyes of the connecting rods 6 6' are forged in place thus forming close 55 workable joints. While this is the preferred

form of construction double-hinge joints or ball and socket joints could be used equally well.

The mechanism pointed out as new is 60 intended to replace any bracing which makes the gangs rigid each independently of the other because such bracing hinders the adjustment in width of the spread arch 11.

It will be observed that when gang 1 65 swings about the pivot 4 the connecting rod 6 is actuated and thereby turns the crank-arm 7 the shaft 8 the crank-arm 10 the crank-arm 10' the shaft 8' and the crank-arm 7' which actuates the connecting rod 70 6' thus causing the gang 1' to swing in opposite direction to that of gang 1. Then the two gangs are so connected that one cannot swing laterally without the other swinging also and when they swing laterally they 75 must either swing toward each other or away from each other. Therefore the two gangs are necessarily rigid except when the spacing between them is being varied. The spacing is either varied or held constant at 80 the will of the operator by means of the adjustable spread arch 11, which enables the operator to make any variation while plowing.

In reference to the rigid gangs it is 85 desired that they be rigid in regard to swinging laterally only. The double eye joints 12 12' allow sufficient flexibility for the gangs 1 1' to be raised or lowered by swinging vertically at the joints 13 13'.

By making the gangs rigid with regard to 90 swinging laterally they are made to yield bodily to the guiding effort imparted through the front arch and to continually sit square with the row and plow equal 95 and parallel strips on both sides of the row thereby contributing to an economical use of the draft power and the guiding efforts of the operator.

These advantages are had in connection 100 with the advantages of the adjustable spread arch which is in easy reach of the operator and connects the gangs directly near the shares by means of which the most accurate variation of the spacing can be 105 readily made thus insuring the proper amount of dirt being thrown to the row under all conditions of operation.

It will be observed that the spread arch 110 cooperates with the new mechanism in making the gangs rigid and the new mechanism cooperates with the spread arch in providing

ing for the variation of the spacing between the gangs.

Having thus described my invention what I claim is,

5. 1. A cultivator provided with two gangs pivoted about vertically disposed axes so as to swing laterally, two vertically disposed shafts journaled to the cultivator frame about vertically disposed axes, means for operatively connecting the lower ends of said shafts each to its corresponding gang, and means for operatively connecting the upper ends of said shafts together, substantially for the purpose described.
10. 2. A cultivator provided with two gangs

pivoted so as to swing laterally, two vertically disposed shafts journaled to the cultivator frame, crank arms and connecting rods operatively connecting the lower ends of said shafts each to its corresponding gang, and 20 meshing crank arms fastened to the upper ends of said shafts.

In testimony that I claim the foregoing as my own, I have hereto affixed my signature in the presence of witnesses.

OSCAR T. HOBSON.
